UNITED STATES PATENT OFFICE.

EUGÈNE FRANÇOIS LOUIS GRANDJEAN, OF BIENNE, SWITZERLAND.

WATCH-REGULATOR.

SPECIFICATION forming part of Letters Patent No. 394,919, dated December 18, 1888.

Application filed July 30, 1888. Serial No. 281,451. (No model.)

To all whom it may concern:

Be it known that I, EUGÈNE FRANÇOIS LOUIS GRANDJEAN, watch manufacturer, of Bienné, Switzerland, have invented an Improvement 5 in Regulators for Watches, of which the following is a specification.

This invention applies to the peculiar construction of the regulator-lever and of the bridge that holds the spindle of the balance, 10 and is adapted, also, to hold the regulator-lever, and I construct this regulator-lever in such a manner that it receives and holds the end jewel or stone for the arbor of the balance-wheel.

15 In the drawings, Figure 1 represents a portion of the watch-works with my improvement applied thereto. Fig. 2 is a section, in larger size, through the regulator-lever and the bridge of the watch at the line *x y*, Fig. 3. 20 Fig. 3 is a plan view, in larger size, of the regulator-lever and part of the balance-bridge.

The three-quarter plate *W* of the watch, the spring-arbor *M*, gear-wheels *E G*, and pinion *F* are to be of any desired character. I have 25 represented such as are usually found in stem-winding watches. The bridge *A* for the balance-wheel is provided with an annular rib, *b*, concentric with the arbor of the balance, but on the top of the bridge, and this rib is 30 undercut or formed as a dovetail, and it is notched to allow for the insertion of the regulator-lever *B*, having arms *d' d''*.

The regulator-lever *B* has a circular portion, *d*, the outer edge of which is beveled to fit within the undercut or dovetailed recess with the annular rib *b*, and there is a segmental channel, *c*, within the circular portion *d* of the lever and a space extending out from this channel between the arms *d' d''*, as shown 40 in Fig. 3, so that this circular portion *d* of the regulator-lever is somewhat similar to a split ring, and by pressing the arms *d' d''* toward each other, as indicated by dotted lines in Fig. 3, the ring *d* can be contracted sufficiently 45 for inserting it into the annular rib *b* or for removing it therefrom. By this construction I am able to apply the regulator-lever upon the bridge of the balance without the use of screws, and at the same time this lever can be 50 swung one way or the other with ease for varying the length of the hair-spring and regulating the watch, as usual, and there is sufficient

friction between the outer edge of the ring *d* and the inner surface of the rib *b* to prevent the regulating-lever *B* turning or getting out 55 of position by any sudden jar or shake to which the watch may be exposed. Within the ring *d* there is a disk, *f*, formed with the rest of the regulating-lever, there being a metal fin, *e*, between such disk *f* and the ring *d*, and this disk *f* is recessed and provided with a hole countersunk from the under side for the reception of the stone or jewel *c*, which rests upon the surface of the bridge *A* and forms the end bearing for the spindle of the balance-wheel. It is often important to be able to remove this jewel *c* to give access to the jewel in the bridge *A*, that receives the end of the balance-arbor, for the purpose of cleaning the parts or repairing the same. This is easily 70 done by simply springing the arms *d' d''* toward each other by the jaws of a pair of pliers and lifting out the regulator-lever from the bridge of the balance-wheel, and it will be seen that there are no screws for holding 75 in the regulating-lever and the jewel *c*; hence the parts can be more reliably made than heretofore, because the screws that have been made use of for holding in the cap-plate and jewel are very small and are liable to be lost 80 or injured in removing or replacing the same, and these I dispense with.

I claim as my invention—

1. The balance-bridge having a notched and undercut annular rib, *b*, in combination with 85 the regulator-lever having a notched ring, *d*, fitting within such annular rib, so that the regulating-lever can be inserted or removed by springing the notched ring, substantially as set forth.

2. The combination, with the balance-bridge, of the regulating-lever having an undercut hole in line with the arbor of the balance and a jewel or stone within such hole forming the end bearing for the balance-arbor, 95 substantially as set forth.

In testimony whereof I have signed my name to this specification in the presence of two subscribing witnesses.

EUGÈNE FRANÇOIS LOUIS GRANDJEAN.
